UNITED STATES PATENT OFFICE

EDGAR ALLEN, OF WICHITA FALLS, TEXAS

LATCH SHACKLE

Application filed October 8, 1927. Serial No. 225,006.

This invention relates to new and useful improvements in a latch shackle.

One object of the invention is to provide a connecting shackle of the character described whereby a traveling block bail, bailer bail, and the like, may be connected to a rope or cable socket in such manner that the connected parts will not come into contact, or become injured when the line, carrying said 10 rope socket, is permitted to slack, or from other causes.

Another object of the invention is to provide a shackle of the character described, which is very strong and durable and which 15 has no projecting parts to hang, or become broken in going into or coming out of the well bore, when the shackle is used in well drilling operations.

A further feature of the invention is to 20 provide a novel form of latch, or latching tool, whereby the shackle may be readily connected to and disconnected from the cable socket.

With the above and other objects in view 25 this invention has particular relation to certain novel features of construction, operation and arrangement of parts an example of which is given in this specification and illustrated in the accompanying drawings, where-

30 in:—

Figure 1 shows an elevational view, partly in section, of one form of the shackle.

Figure 2 shows an edge view of a connecting link employed.

Figure 3 shows an end view of said link.

Figure 4 shows an elevational view of a slightly modified form of the shackle, partly in section and

Figure 5 shows a side view of a connecting 40 link employed in this form.

Referring now more particularly to the drawings, wherein like numerals of reference designate similar parts in each of the figures, the numeral 1 designates the body of the 45 shackle which is formed with the end eyes 2, 2, one to receive the cable socket latch having the eye 3, and the other to receive the bail 4, of a traveling block, bailer, or the like.

The main body of the shackle is of a general 50 elliptical form and between the eyes 2, 2, is

thickened inwardly. One side of the shackle is removable. In the form shown in Figure 1 this removable part comprises a bar 5 whose ends are formed with mortises 6, 6 dovetailed in form in which the correspondingly shaped tenons 7, 7, of the abutting parts of the body 1 interlock and these interlocking parts are further secured together by means of the bolts 8, 8, which are fitted inwardly through them and whose heads are countersunk in said bar. The inner ends of these bolts are threaded to receive the nuts 9, 9, which are also countersunk into the corresponding tenons 7 to the end that the shackle will have no unnecessary projections to cause the shackle to hang, when in use. The bar 5 has the inwardly extending spaced clamp flanges 10, 10, which embrace the relatively flat inwardly extending tongue 11, into which the inwardly thickened portion of the body 1 is formed. The outer sides of the clamp flanges 10 are substantially flush with the outer side of the adjacent parts of the body 1 to give the shackle a smooth outside contour and a set screw 12, is fitted through said clamp flanges and tongue with its head countersunk into one of said flanges and its other end threaded into the other clamp flange.

In the form shown in Figure 4 the bar 5' has the dovetailed end mortises 6' 6' adapted to receive, and interlock with, the corresponding end tenons 7' 7', into which the adjacent parts of the shackle body 1' is formed. These interlocking parts are further secured together by means of set screws 8', 8' which are fitted inwardly therethrough and whose heads are countersunk into the bar 5 and whose inner ends are threaded through the tenons 7' 7'.

The bar 5' is thickened inwardly and said thickened portion is formed with a tenon 10' which fits snugly into a mortise 11' provided in the inwardly thickened mid portion of the body 1' and a set screw as 12' is fitted through said body 1' and said tenon 10'. This type of shackle also has a comparatively smooth exterior surface.

By the use of the type of shackle hereinabove described the connected parts will be

kept apart and will be better protected and consequently will not be so subject to wear or injury.

While I have shown what I now consider the preferred forms of the device it is obvious that mechanical changes and adaptations may be made within the scope of the appended claims.

What I claim is:—

- 10 1. A shackle of general elliptical form, having end eyes and formed of separable complemental parts, one part comprising a removable side bar whose ends are formed with mortises, said bar also having inwardly extending spaced clamp flanges intermediate its ends and having a slot between them, the other complemental part having tenons which fit into said mortises and also having a wide, relatively flat, inwardly extending tongue fitted into said slot between said clamp flanges, bolts securing said tenons in said mortises and a set screw securing said tongue between said clamp flanges.
- 15 2. A shackle having end eyes and formed of separable complemental parts, one part comprising a removable side bar and the other part having facing, spaced ends, said bar and the adjacent ends of said other complemental part being formed one with tenons and the other with mortises adapted to receive said tenons, means passing through said intermeshing parts to secure said bar in place said bar and the other complemental part being each extended inwardly and one being formed with clamp flanges, spaced apart to form a slot between them and the other with a wide, flat, tongue which fits in said slot between said flanges and a securing means passing through said flanges and tongue to secure them together.

In testimony whereof I have signed my name to this specification.

EDGAR ALLEN.
